(57) **CLAIM**

The ornamental design for a combined airtight lid and container, as shown and described.

DESCRIPTION

FIG. 1 is a perspective view of the combined airtight lid and container for storing food and other items in accordance with the present invention, the stippling in FIGS. 1, 3, 5 and 7-10 representing a textured or frosted appearance;

FIG. 2 is a top plan view of the lid/container of FIG. 1;

FIG. 3 is a bottom view of the lid/container of FIG. 1;

FIG. 4 is a side elevational view of the lid/container of FIG. 1 with one of the lid latches in an up non-receiving position, the view of both sides being identical;

FIG. 5 is an unassembled perspective view of the lid/container of FIG. 1;

FIG. 6 is a side elevational view of the lid per se with both latches in an up position;

FIG. 7 is an additional top plan view of the lid/container of FIG. 1 positioned on the same sheet with like lid/containers having different dimensions;

FIGS. 8, 9 and 10 are top plan views of the lid/containers similar to the lid/containers of FIG. 1, but having different dimensions, the bottom views will be the same as FIG. 3 except for the dimensions;

FIG. 11 is a front view of the lid/containers of FIGS. 8 and 9 looking from the left of the figure;

FIG. 12 is a side view of the lid/containers of FIGS. 8, 9 and 10, looking from the bottom of FIGS. 7 and 8 and from the left of FIG. 10; and,

FIG. 13 is a front view of the lid/containers of FIGS. 9 and 10 looking from the bottom.
